UNITED STATES PATENT OFFICE

JOSEPH BULOVA, OF NEW YORK, N. Y., ASSIGNOR TO BULOVA WATCH COMPANY, INC.,
OF NEW YORK, N. Y., A CORPORATION OF NEW YORK

WATCH

Application filed March 24, 1927. Serial No. 177,933.

The invention relates to watches and watch-cases, and the object is to provide a very economical and advantageous construction suitable for small watches.

5 Watches have long been known wherein the movement is inserted from the rear into a body integral with the front bezel. It has also long been common in these and other watches to hold the movement in the case by 10 means of a ring which closely encircles the sides of the movement and closely fits into the body of the case. Such a ring may also serve to prevent the entrance of dust into the sides of the movement. It is also known from the 15 Marotti Patent No. 1,496,859, dated June 10, 1924, to combine a flanged ring encircling the movement with a flexible, transparent shield covering the back of the movement, the shield being retained by the ring, and very advan- 20 tageous protection for the movement being secured.

One of the features of the present invention consists in exceedingly simple and very effective means for positively catching such a ring 25 or band in the case, giving great security for the movement or firm retention for the shield, and permitting ready insertion by simply pushing the ring in until it snaps, and ready removal by simply pulling or prying the ring 30 out. The ring is made of a thin band of metal, from which individual small protuberances are forced out to snap under the edge of an inwardly projecting fixed flange of the case body. These protuberances can be dis- 35 posed at those points in the circuit of the band where there will be the most suitable amount of fixed flange for their engagement, this de- 40 pending upon the relation between the shape of the case and of the movement, which usually differ from each other so that the fixed flange into which the movement is inserted is of varying widths in different places, and at certain regions may disappear. The localized yielding afforded by such protuberances 45 makes practicable the insertion and removal of the band in the exceedingly small dimensions of such watches, while gaining the advantage of the secure holding. The band is provided at the rear with an external ledge 50 which overlaps the fixed flange, forming a

stop and a joint-closer, and the edge of the fixed flange is embraced between this ledge on the outside and the protuberances on the other side. Another ledge or flange projecting inwardly of the rear edge of the band overlaps the back of the movement around the edge and retains the flexible, transparent shield. 55

Other features and combinations of the invention will become apparent as the specification proceeds. 60

In the accompanying drawing forming part hereof:

Fig. 1 is a diagonal sectional view through a watch embodying the invention, the section being taken on the plane indicated by the line 1—1 of Fig. 2, the watch being shown closed in Fig. 1 and with the bezel up; 65

Fig. 2 is a rear view looking at the back of the movement, with the back of the case opened; 70

Fig. 3 is a rear view of the body of the case and the band, the rear end of the latter with its flanges or ledges having been cut away, the movement and the case back being omitted; 75

Fig. 4 is a perspective view of the band or ring. 75

The body 1 and bezel 2 are preferably made in one shell, and the back 3 is hinged to the body. A sheet-metal piece 4 is soldered into the body shell, this piece having a wall 5 which is telescoped into the surrounding wall of the shell, forming two thicknesses, the wall 5 projecting beyond the rear edge of the shell so as to form a neck to receive the flange 6 of the back 3. 85

From the rear edge of the wall 5 of the inner piece a flange or overhang 7 is extended inward, the opening in this flange following the lines of the movement 8, which may be elliptical as shown, while the case may be rectangular, oblong or other shape. A fixed flange of varying width is thus provided to receive the movement, which is inserted into the flange from the rear. 95

A band 9 encircles and closely fits the sides of the movement, abutting at the front against a ledge or shoulder 10 with which such movement's are customarily provided. This ring also fits closely into the opening 100

of the flange 7, which it overlaps at the back by a narrow flange or ledge 11 suitably formed outward from the rear edge of the band. An inturned flange 12 on the same 5 end or edge of the band projects inward over the edge of the movement, and holds the edge of a celluloid or like shield 13 between it and the movement.

At four suitable points, or other points few 10 in number and widely spaced about the circuit of the band, the thin metal thereof is forced or struck outward to make the small rounded protuberances 14. These are spaced from the flange or ledge 11 by approximately 15 the thickness of the metal of the fixed overhang flange 7, so that when the band is pushed into place the edge of the opening in said flange 7 is held between the protuberances and the ledge 11.

20 The movement may be put in the case first, and the band 9 may then be inserted with the shield, or the shield having been laid on the back of the movement; or the band, shield and movement may be assembled outside and 25 pushed together into the case. In both introducing and removing the band it is not necessary to snap all the protuberances past the edge of the fixed overhang at one time, since the protuberance or protuberances at 30 one end or side can first be forced past the overhang and then the others, making it possible to seat and unseat the band without too much effort or strain in these small, delicate watches.

35 I claim:

1. In a watch-case, the combination of an inwardly extending flange the inner edge of 40 which follows the shape of the movement, and a removable thin band fitting about the movement within the opening of said flange, said band being formed with individual small 45 external protuberances adapted to snap and hold under said edge, nevertheless permitting the band to be readily inserted and withdrawn by reason of the slight localized yielding.

2. In a watch-case, the combination of an inwardly extending flange the inner edge of which follows the shape of the movement, and a removable thin band fitting about the movement within the opening of said flange, said band being formed with a peripheral ledge to overlap the inner edge of said flange and with individual small external 55 protuberances adjacent said ledge adapted to snap and hold under said edge, nevertheless permitting the band to be readily inserted and withdrawn by reason of the slight localized yielding.

60 3. In a watch-case of shape different from that of the movement, the combination of a body shell into which the movement is inserted from the rear, a case back, a piece telescoped into the wall of the body forming a wall of double thickness, the rear portion of

said piece projecting from the body to form a neck to receive said back; said piece having an inwardly extending flange the inner edge of which follows the shape of the movement, and a removable thin band fitting about the movement within the opening of said flange, said band being formed with individual small external protuberances adapted to snap and hold under said edge, nevertheless permitting the band to be readily inserted and withdrawn by reason of the slight localized yielding.

4. In a watch, the combination of an inwardly extending rear flange forming part of the case, the inner edge of which flange 80 follows the shape of the movement, and into which the movement is inserted from the rear, a flexible transparent shield covering the back of the movement, and a removable thin band fitting closely about the movement and into said flange, said band being formed with means at its rear edge for retaining said sheet and with individual small external protuberances in its wall adapted to snap and hold under the edge of said flange.

5. In a watch, the combination of an inwardly extending rear flange forming part of the case, the inner edge of which flange follows the shape of the movement, and into which the movement is inserted from the rear, a flexible transparent shield covering the back of the movement, and a removable thin band fitting closely about the movement and into said flange, said band being formed at the rear with an internal flange 100 to overlie the back of the movement and being also formed with individual small external protuberances in its wall adapted to engage under the edge of said case flange, said protuberances being of such character 105 as to permit the band to be withdrawn from the case.
